DISPENSING CONTAINER

Henry A. Fink, Pelham Manor, N. Y., assignor to
 Continental Can Company, Inc., New York,
 N. Y., a corporation of New York

Application August 19, 1940, Serial No. 353,294

1 Claim. (Cl. 221—11)

The present invention relates to new and useful improvements in dispensing containers, and more particularly to improvements in a container having a closure and a pouring spout adapted to be attached thereto for dispensing the contents of the container.

In general, the invention contemplates the provision of a container having an opening therethrough which is closed by a bung closure to which a pouring spout is adapted to be readily attached. Preferably, the bung closure has a scored portion which may be removed to provide a dispensing opening to permit the pouring of the contents therethrough onto the pouring spout. A friction closing plug is adapted to co-operate with the pouring spout for resealing the container after the scored portion on the bung closure has been removed. Containers of this type are generally used for dispensing various fluids and a container of this general type is shown in United States Letters Patent No. 2,196,426, issued to Frank J. O'Brien on April 9, 1940. The present invention is concerned with a form of dispensing container which is particularly adapted for use with syrup or other liquids which become tacky or sticky.

An object of the present invention is to provide a dispensing container of the above type wherein the friction closing plug makes substantially a line contact with the container so as to reduce the tendency of the plug to stick to the container, thus facilitating removal thereof.

Another object of the invention is to provide a dispensing container of the above type wherein the pouring spout is provided with an inward bead within the bung closure, this inward bead being relatively small and providing substantially a line contact for the friction closing plug.

The above and other objects of the invention will in part be obvious and will be hereinafter more fully pointed out.

In the accompanying drawing:

Figure 1 is a top plan view of the container with the pouring spout attached thereto, the pouring spout being shown in dotted lines disposed within the side wall of the container.

Figure 2 is a side elevation of Figure 1, partly in section.

Figure 3 is an enlarged fragmentary side view, in section, showing the bung closure, the pouring spout and the friction closing plug in assembled position.

Referring more in detail to the accompanying drawing, one form of the invention is shown for purposes of illustration. There is shown a con-

tainer having a rectangular body portion 10 to which a can end 11 is secured by the usual double seam 12 or the like. It is to be clearly understood that the body portion of the container may be of any desired shape and that the can end 11 may be secured thereto in any suitable manner. The can end is depressed substantially within the upper end of the body portion and is provided with an upstanding neck portion 13 which extends around the edge of a filling opening there-

in. A cup-shaped bung closure 14 is provided for closing the filling opening in the can end and this bung closure includes a cylindrical and substantially vertical wall portion 15 and a bottom closing wall portion 16 which is disposed substantially in line with the surface of the can end. The free edge 15a of the wall portion 15 is shaped to overlie and engage the free end of the neck portion 13 on the can end and may be secured thereto in any suitable manner. The cylindrical wall portion 15 on the bung closure is provided with an inward projection, preferably in the form of an inwardly extending annular rib 17, which is illustrated as being disposed intermediate the ends of the wall portion 15 on the bung closure and spaced above the bottom wall 16 thereof. This inward bead 17 provides a holding rib or shoulder for removably and rotatably securing the pouring spout to the container in a manner to be hereinafter more fully pointed out. The bottom wall portion 16 of the bung closure includes a central portion 16a which is defined by a score line 18 and this central portion is adapted to be removed in order to provide a dispensing opening through which the contents of the container may be poured.

A pouring spout 19 is constructed so that it may be readily attached to the bung closure and is provided with a pouring lip 20 and a depending cylindrical wall portion 21. The depending cylindrical wall portion 21 is adapted to fit within the wall portion 15 of the bung closure and the bottom of the cylindrical wall portion 21 is provided with a relatively small inwardly curled bead 22 which is substantially closed. The inner edge 22a of the bead 22 is for the purpose of providing substantially a line contact for a friction closing plug 23. The inner edge 22a of the bead 22 is disposed approximately above the score line 18 on the bottom wall 16 of the bung closure. The depending wall portion 21 of the pouring spout is cut to provide a plurality of outwardly extending lugs 24 which are adapted to snap beneath the rib 17 on the

bung closure so as to removably maintain the pouring spout in position and to also permit rotation of the pouring spout relative to the can end.

The friction closure 23 is in the form of a plug having a bottom closing wall 25 and an upstanding cylindrical wall portion 26. The free edge of the cylindrical wall portion 26 is provided with a strengthening bead 27. This friction plug 23 is adapted to be positioned within the cylindrical wall portion 21 of the pouring spout in such a manner that the outer surface of the cylindrical wall portion 26 thereof will frictionally engage and make line contact with the inner surface 22a of the bead 22 on the pouring spout.

When the container has been filled and the bung closure 14 secured to the upstanding neck portion 13 on the can end, the pouring spout 19 may be attached directly to the bung closure, or it may be furnished separately for subsequent attachment thereto. Similarly, the friction closing plug 23 may be attached within the pouring spout and thus transported as a unit. In attaching the pouring spout 19 to the bung closure, it is forced inwardly of the bung closure so that projections or lugs 24 will snap beneath the rib 17 and thus provide a snap connection between the bung and the spout. Thus, the pouring spout can be rotated relative to the can end so that the lip portion 20 will extend over the double seam in a dispensing position or so that it may be disposed within the side wall of the container, as shown by the dotted lines in Figure 1.

When it is desired to dispense the contents of the container, or any portion thereof, the friction closing plug 23 is removed from engagement with the bead 22 on the pouring spout. The central portion 16a on the bottom of the bung closure is punched and removed along the score line 18 so as to provide a dispensing opening. The contents of the container may now be poured through the pouring lip 20 over the edge of the container. If only a portion of the contents is to be dispensed, the friction closing plug 23 may be again fitted within the pouring spout so as to close the dispensing opening through the bung closure. As indicated above, the cylindrical wall portion 26 of the closing plug 23 makes substantially a line contact with the inner edge 22a of the bead 22 on the pouring spout so as to minimize the tendency of syrup or similar fluid to cause the closing plug to stick in the resealed position. The bead 22 on the pouring spout is slightly resilient and the closing plug 23 is forced within the same so as to afford tight friction sealing contact.

From the foregoing description, it will be seen that the present invention provides a highly efficient dispensing container which is particularly adapted for use with syrup or other fluids which tend to become sticky. The pouring spout is connected to the bung closure for rotation relative thereto so that it may be swung inwardly of the double seam around the end of the container. In a dispensing position, the pouring spout extends just over the double seam. When the scored portion of the bung is removed for

providing a dispensing opening, the contents may be poured therethrough and through the open bottom end of the vertical wall portion of the spout. When it is desired to reseal the container, the closing plug is inserted within the cylindrical skirt portion of the spout so as to make friction contact with the inward bead around the bottom edge thereof. This inward bead is slightly flexible so as to assure a tight sealing contact entirely around the vertical wall portion of the plug. The innermost edge 22a of the bead 22 provides a line surface so that the closing plug will make substantially a line contact therewith. With such a construction, the tendency of the sticky fluid to prevent reopening of the container is reduced in that the closing plug, because of the line sealing contact, can be readily reopened. The bottom surface of the inward bead 22 also makes substantially a line contact around the remaining surface of the bottom closing wall 16 on the bung closure so as to facilitate rotation of the pouring spout from operative to inoperative positions. The bead 22 is substantially a closed bead so as to prevent accumulation of fluid although the bead is slightly resilient so as to insure tight seal contact entirely around the closing plug.

While one form of the invention has been shown for purposes of illustration, it is to be clearly understood that various changes in the details of construction and arrangement of parts may be made without departing from the scope of the invention as set forth in the appended claim.

I claim:

A container comprising a body portion, a container end secured to said body portion and having an opening therethrough surrounded by an upstanding neck portion, a cup-shaped closure for the opening and secured to said neck portion with the side wall of said cup-shaped closure provided with an inwardly projecting peripheral rib intermediate the ends thereof, the bottom of said cup-shaped closure being scored to permit removal thereof for dispensing, the contents of the container, a spout having a pouring lip and an open-ended depending wall portion extending into the cup-shaped closure with the said depending wall portion cut and shaped to form outwardly extending spring lugs adapted to snap beneath the rib on the cup-shaped closure, the depending wall portion of said spout also having the bottom edge thereof below the lugs rolled inwardly and outwardly to provide a bead, contacting with the bottom of the cup-shaped closure and having the innermost surface thereof extending inwardly of the said wall portion, and a friction plug adapted to extend within the wall portion of the spout and making line frictional contact with the innermost surface of said bead for spacing the wall of the friction plug inwardly from the inner surface of the wall portion of said spout whereby to limit the contacting area substantially to a line contact when the container is closed in order to reduce the tendency for the friction plug to stick when employing tacky materials.

HENRY A. FINK.
